UNITED STATES PATENT OFFICE

GUS GOLDBERG, OF NEW YORK, N. Y.

DESIGN FOR A TORCHÈRE

Application filed November 17, 1931. Serial No. 41,759. Term of patent 3½ years.

To all whom it may concern:

Be it known that GUS GOLDBERG, a citizen of the United States of America, residing at New York, in the county of New York and State of New York, has invented a new, original, and ornamental Design for a Torchère, of which the following is a specification, reference being had to the accompanying drawings, forming part thereof.

Figure 1 is a front elevation of a torchère, and

Figure 2 is a side elevation thereof, the opposite side of the base being substantially identical.

I claim:

The ornamental design for a torchère, as shown and described.

GUS GOLDBERG.
